UNITED STATES PATENT OFFICE.

EMMANUEL THOMAS COOK, OF ALEXANDER, ASSIGNOR OF ONE-HALF
TO F. M. CARLTON, OF CARLTON P. O., TEXAS.

BAND-CUTTER AND FEEDER FOR THRASHERS.

SPECIFICATION forming part of Letters Patent No. 314,805, dated March 31, 1885.

Application filed October 30, 1884. (No model.)

To all whom it may concern:

Be it known that I, EMMANUEL T. COOK, a citizen of the United States, residing at Alexander, in the county of Erath and State of Texas, have invented certain new and useful Improvements in Band-Cutters and Feeders for Thrashers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a vertical sectional view of my device. Fig. 2 is a plan view of the same. Fig. 3 is a cross-sectional view, and Figs. 4 and 5 are detail views.

This invention relates to improvements in band-cutters and feeders for thrashing-machines; and it consists in the construction and novel arrangement of parts, hereinafter fully described, and pointed out in the claims.

In the drawings accompanying and forming part of this specification, A represents the frame of the machine, and a a side hooks at its tail, or other proper arrangement for attaching it to the thrasher. a' is a vertical beam rising centrally from near the front of frame A, and serving a purpose hereinafter explained.

B is the main or driving shaft journaled transversely in proper bearings across the lower part of the frame A, and b b' are pulleys on the same, to one side, by the former of which and a belt the machine is run from the thrasher, and the latter of which, by means of a pulley, c, and belt, runs the apron C, which runs over proper end rollers, c' c', journaled in the frame A. The apron is preferably made with the transverse wooden bars c' forming part thereof.

D is a central crank on the driving-shaft B, which actuates the vertical pitman d, having its upper end pivoted to the front end of the lever or arm E that carries the knives. The said lever is pivoted between the arms of the forked upper ends of the beam a', and is made vertically and longitudinally adjustable thereon by means of the holes e and the holes e' in the beam and arm respectively. e' is a bar above the lever E, likewise pivoted in one of the

holes e of the beam a' and adjustable vertically thereon.

F F are the similar cutter-bars, having the edges saw-shaped and arranged to reciprocate alternately side by side, and to lift by means hereinafter described. f f are swinging bars pivoted by their lower ends to the rear ends of the cutter-bars, and by their upper ends to the lever E. f' is a similar bar pivoted to one cutter-bar and lever E in front of the bar f, and f' a longer bar pivoted to the other cutter-bar, to the lever E and end of the bar e' opposite to the bar f'. f' are brace-rods issuing from the bars f' and f' and serving to hold the cutter-bars side by side. The bars f, f', and f' are so arranged with relation to the beam a', lever E, bar e', and cutting-bars, that the latter are made to reciprocate alternately while moving up and down. The band of the bundle being caught between the saw-teeth of the two cutter-bars, is consequently sheared off.

G G are the similar platforms which receive the bundles and direct them to the cutter-bars. These platforms are secured opposite each other to the frame A by the similar springs, g g, which connect the front corners to the beam a', the similar vibrating arms, g' g', pivoted to their front corners and to the frame, and the slotted similar arms, g' g', which are pivoted by their inner ends to the rear corners of the platforms, and are attached to the frame by their slots and set-screws passing through it. The platforms may, by means of said slots, be placed at different distances apart to accommodate different-sized bundles, and when they have been pushed slightly downward by the action of the bundles and mechanism and rotated slightly on the arms g' and g', the springs g will return them to place. g' are the inwardly-extending fingers of the platform, which fingers catch and hold the grain and allow the cutting-bars to act between them.

H H are swinging bands or straps of leather or other suitable material fixed one on each side and within the frame A at its tail end, and h h are parallel rollers journaled in bearings fixed to said straps. The straps and rollers are so arranged in relation to one another and to the apron as to keep the grain compressed as it passes out of the binder to the thrashing-machine.

I is a crank made on the shaft B at the end opposite the pulleys *b* and *b'*, and *i* is a horizontal connecting-rod actuated—that is, reciprocated—by said crank.

5 J is a vertical shaft oscillating in proper bearings fixed to the frame and having standing out from it near its foot the crank-arm *j*, which connects by its outer end and is vibrated by the rod *i*. *j'* is a similar crank-arm 10 standing in from the shaft J near its top above its upper bearing.

15 K is a transverse reciprocating rod, one end of which pivots over the end of the crank-arm *j'* and is actuated thereby, and the other end passes over and is supported by a roller, *k*, having bearings in the opposite side of the frame. *k'* is a vertical rod depending from the rod K near the center of the machine and serving by the transverse motion imparted to 20 it by the rod K to spread the ends of the bundles so that they can be more readily cut.

In operating the machine after it is attached by the hooks *a a* to the thrashing-machine, the bundles are run upon the platforms G and 25 fall down upon the points *g'*. The action of the cutter-bars now comes into play, severing the bands and allowing the loosened grain to fall upon the apron, which carries and delivers it to the thrashing-machine. The rollers *h h* 30 press down on the grain as it passes out of the band-cutter and make it deliver more compactly to the cylinder of the thrasher. The cutter-bars are made long enough to engage and cut the band wherever they may fall upon 35 the platform.

Having thus described my invention, what I desire to secure by Letters Patent is—

1. In a band-cutter for a thrasher, the combination, with the main frame A, main shaft B, platforms G G, and mechanism adapted and 40 arranged to cut the bands, of the crank I, rod *i*, oscillating shaft J, provided with the crank-arms *j* and *j'*, reciprocating rod K, and depending rod *k'*, substantially as specified.

2. In a band-cutter for a thrashing-machine, 45 the combination, with the main frame A, platforms G G, and reciprocating cutter-bars F F, of the main shaft B, crank D, pitman *d*, bars E *e'*, and swinging straps or bars *f*, *f'*, and *f''*, substantially as specified.

3. The combination, in a band-cutter, with 50 the main frame and the platforms G G, of the spring *g*, vibrating arms *g'*, and slotted arms *g''*, adjustable on the main frame, substantially as specified.

4. The combination, with the main frame, 55 of the crank-shaft B, pitman *d*, bar E, the upright *a'*, the parallel cutters pivotally suspended from the said bar E, the pivoted bar *e'*, and the lever *f''*, connecting one of the cutters with the bars E and *e*, substantially as specified.

In testimony whereof I affix my signature in presence of two witnesses.

EMMANUEL THOMAS COOK.
